DESIGN FOR COMBINED SUNGLASSES AND SCARF

George Stangl, New York, N. Y.

Application May 15, 1948, Serial No. 146,390

Term of patent 3½ years

(Cl. D57—1)

To all whom it may concern:

Be it known that I, George Stangl, a citizen of Hungary, residing in New York, county of New York, and State of New York, have invented a new, original, and ornamental Design for Combined Sunglasses and Scarf, of which the following is a specification, reference being had to the accompanying drawing, forming part thereof.

The figure on the drawing is a perspective view of combined sunglasses and scarf, showing my new design.

I claim:

The ornamental design for combined sunglasses and scarf, substantially as shown.

GEORGE STANGL.
